UNITED STATES PATENT OFFICE

2,592,606

BAR MILLER

Theodore S. See, Hammond, Ind., and Horace A. Frommelt, Milwaukee, Wis., assignors to La Salle Steel Company, Chicago, Ill., a corporation of Delaware

Application February 10, 1948, Serial No. 7,375

4 Claims. (Cl. 90—11)

1

This invention relates to a machine for milling metal bars and more particularly to an improved machine for milling metal bar stock other than rounds. Such stock includes squares, flats, hexagons and what are termed "special sections." This latter term indicates an elongated metal article of uniform, cross section, the cross-sectional shape thereof being neither square, flat, hexagonal, octagonal nor round.

The invention has for an important object thereof the provision of a new and improved machine of this character which is operable at much higher speeds than heretofore deemed possible and which is flexible in design and adjustment in order to enable it to be set up quickly and with greater facility than the machines of the prior art to operate on metal bars, including special sections, of various shapes and sizes.

A feature of the invention which contributes to the accomplishment of the foregoing object consists in providing, in a machine of this character, a plurality of independently adjustable cutters, positioned in tandem with respect to one another, each cutter being preferably driven at speeds in excess of those heretofore employed in the art. In copending application Serial No. 7,372 filed February 10, 1948, in the name of one of the instant inventors there is disclosed an improved milling process for steel and its alloys and also a machine for practicing the method in the milling of round bars. The present invention may, in some of its aspects, be regarded as residing in the provision of a novel machine capable of applying the method of the copending application to the milling of metal bars other than rounds. Primarily the novelty of the method phase of this development, of which the instant application is a part, relates to steel and its alloys although many features of the development such as the apparatus, cutters, etc., are not to be confined to such materials but will apply with equal force to the milling of other ferrous, as well as non-ferrous metals.

Furthermore, although both this and the copending application disclose machines for milling bars, the invention, including the method, may be employed in a novel manner in milling such additional products as billets, slabs, blooms, rounds, tube rounds, etc., as well as apparatus, devices, articles and machines manufactured from such products.

A further feature of the invention which contributes to the flexibility of the machine herein disclosed consists in the provision of a novel cutter assembly in which the milling cutter, made pref-

2

erably of a carbide material, is made up of a plurality of sections, keyed and clamped together to form a complete assembly. In accordance with this feature of the invention the parts or sections of various cutters may be interchanged with one another to adapt the assembly to operate on bars of various shapes, sizes and cross sections thereby avoiding the necessity of providing separate, complete cutters for each different size or shape of bar.

Other objects and features of the invention will become apparent from a reading of the following specification in the light of the accompanying drawings, in which,

15 Figure 1 is a diagrammatic view of a milling machine constructed in accordance with the present invention;

Figure 2 is a view in front elevation of a single stand, or assembly, of a cutter and guide shown, 20 in plurality, in Figure 1;

Figure 3 is a view, partially in section, of the stand or assembly shown in Figure 2;

Figure 4 is a view, in front elevation, showing the manner in which the cutter and guide are 25 driven;

Figure 5 is a view in side elevation of the construction shown in Figure 4;

Figures 6 to 9 inclusive illustrate the component parts of a typical cutter assembly constructed in 30 accordance with the present invention, and

Figure 10 shows three typical "special sections" made from bars of different shapes.

As diagrammatically shown in Figure 1 of the drawings, the machine comprises a suitable number of stands or assemblies A, B, C, etc., each of which, as illustrated, is made up of a cutter 10 and a guide roll 12 cooperating therewith. A work piece 14, which for purposes of description, may be regarded as a square is shown passing 35 through the machine, and, more specifically, passing between the cutters 10 and the cooperating guide rolls 12. It will be understood that the cutters 10 will mill the top and bottom surfaces of the bar and in order to accommodate bars of different thicknesses or shapes, the distance between the guide rolls and cutters may be increased or decreased through the provision of adjusting means which will presently be described.

In order to mill the sides of the bar as it passes 40 through the machine the latter is provided with a second series of stands or assemblies M, N, O, etc., each of which, as illustrated, comprises a cutter 10 and a cooperating guide roll 12. It will be appreciated that a greater or lesser number 45 of stands or assemblies A, B, C, M, N, O, etc.,

may be provided, as desired, in accordance with the demands of the work being performed by the machine. Also it is not necessary to operate simultaneously all of the stands or assemblies with which the machine may be provided. Certain of them may remain idle during a given milling operation but may be brought into operation during another. Additionally, the arrangement of cutters and guide rolls, as illustrated in Figure 1, may be changed, as desired, without departing from the scope of the invention as herein set forth. Thus, the vertical cutters and guide rolls M, N, O might be interposed between the horizontal cutters and guides A, B, C to provide alternate horizontal and vertical stands. Various other permissible and contemplated arrangements of the stands as well as the cutters and guide rolls within the stands will occur to those skilled in the art.

Feed rolls 16 and 18 may be provided, and, if desired, burnishing rolls 20 and 22 may be added. These latter operate at surface speeds above the rate of feed of the bar to impart a burnishing action thereto. Similarly, the guide rolls 12 may rotate faster than the bar moves to obtain the burnishing action.

As hereinbefore set forth, the machine is so designed as to obtain a maximum amount of flexibility in operation in order to render it capable of milling bars of various shapes and sizes, including hexagons and octagons as well as bars having cross-sectional contours of irregular shape, which latter are known in the trade as "special sections." To this end, as shown in Figure 2, the cutter 10 and guide roll 12 are mounted in a hood or casing 24 which, in turn, is mounted for rotation within an outer frame or casing 26. Roller bearings 28 facilitate the rotation of the hood 24 within the casing and, as shown in Figure 3 these members may be provided with collars 30 having engagement with an annular groove 32 formed in the outer surface of the hood 24. Members 33 are provided for the purpose of maintaining the hood 24 in proper position within the casing 26 and a rack 34 provided with a pinion 36 afford means for adjusting the rotary position of the hood 24 within the frame 26. A hand operated member 40 is provided for driving the pinion 36 although it will be appreciated that this member may be replaced by electrically driven means, remotely controlled, if desired.

Turning now to Figures 4 and 5, it will be observed that the cutter 10 is mounted on a shaft 42 which is rotatably driven by means of high speed motors 44 and 46 mounted on platforms 48 and 50 carried by the hood 24. The guide roll 12 is mounted on a shaft 52 which, through interconnections, is driven by high speed motors 54 and 56. These latter drive bevel gears 58, 60 which have driving engagement with cooperating bevel gears 62, 64 carried by sleeves 66, 68 splined to shafts 70, 72. Thus the latter rotate with the sleeves 66, 68 but are free to move upwardly or downwardly through such sleeves.

At their upper extremities the shafts 70, 72 carry bevel gears 74, 76 which have driving engagement with bevel gears 78, 80 fixed to the opposite ends of the guide roll shaft 52. The bevel gears 74, 78 and 76, 80 are constantly in driving engagement with one another owing to the fact that they are mounted within brackets 82, 84. Examining one of the brackets, for instance the one which appears to the left of the guide roll 12, as shown in Figure 4, an integrally formed

arm 86 extends outwardly therefrom and carries a bushing 88 within which the shaft 70 freely rotates. A second arm 90, also integrally formed with the bracket 82 extends rearwardly and carries a bushing 92 within which the guide roll shaft 52 freely rotates. Thus the arms 86 and 90, being formed integrally with bracket 82 move up and down as a unit and at all times the bevel gears 74 and 78 remain in driving engagement with one another. Inasmuch as the bracket 84 which supports the bevel gears 80 and 76 is identical to the bracket 82 no detailed description of it need be given.

In order to vary the position of the brackets 82 and 84 and thereby to control the distance between the cutter 10 and the guide roll 12, the brackets are mounted on screw threaded shafts 94, 96, rotation of which causes the brackets to move uniformly upwardly or downwardly thereby changing the position of said guide roll 12. Rotation of the shafts 94, 96 is accomplished in the following manner. The shaft 94 is extended and carries at its lower extremity a bevel gear 98 having screw threaded engagement with a bevel gear 100 carried on the inner end of a hand-operated adjusting means 102. The upper portion of the screw threaded shaft passes through a bushing 104, carried by a bracket 106, and has a gear 108 affixed to its terminal portion. A chain 109 is provided for the purpose of transmitting rotary motion from the shaft 94 to the cooperating shaft 96. Thus movement of the hand-operated member 102 causes the shafts 94, 96 to rotate in one direction or the other, thereby making the guide roll 12 move toward or away from the cutter 10.

The latter member, namely the cutter 10 is mounted on a shaft 110 which is carried by bushings 112, 114 formed integrally with the brackets 106, 107. The shaft is provided with clutch couplings 112a, and 114a which may be quickly and conveniently disconnected to permit ready interchangeability of cutters.

As previously mentioned, one of the most important features of the invention is its great flexibility of set-up and operation which enables it to operate satisfactorily on bars of regular cross-sectional contour such as squares, flats, hexagons and the like and also on bars of irregular cross-sectional contour known as special sections. In milling flats and squares, only horizontal cutters and guide rolls for the top and bottom of the bar and vertical cutters and guide rolls for the sides will be required. On the other hand, in milling a hexagon, for instance, in one pass or operation, it will be necessary to rotate at least two of the stands or assemblies A, B, C, etc., M, N, O, etc., into a position such that cutters 10 will be positioned to mill the two additional faces presented by the bar. In the case of octagons, four of the stands or assemblies will be rotatably positioned to operate upon the four additional faces that are presented. Thus the machine can be quickly and easily adjusted to accommodate these different types of bars and to facilitate matters in setting the machine for these different purposes it is proposed to employ an indicator and corresponding indicia in connection with each stand or assembly A, B, C, X, T, N, O, to record visibly its exact setting.

Coming now to the operation of the machine in milling special sections, i. e., bars having irregular cross-sectional contours, Figure 10 shows three typical shapes of bars of this character. As stated the invention contemplates milling

these or other such shapes with the same facility and rapidity as flats, squares, hexagons and the like. To this end it is now proposed to employ cutters and guide rolls of a special design that are shaped to conform to the shape of the special section being milled. It is further proposed, in order to reduce the cost of cutters and possibly guide rolls, to build them up in interchangeable sections which can be assembled to provide a unit shaped to conform to the contour of the bar being milled.

In Figures 6 and 7 there is shown a cutter of the type disclosed in copending application Serial No. 7,372, referred to above. Such a cutter is monolithic in construction and is made, for example of so-called hard metal. The so-called hard metal is usually an alloy of carbides, borides, nitrides or silicides and the cutter comprises a body portion 120 integrally formed of such metal and provided on its exterior, peripheral cutting face with a series of ground, spiral or helical cutting teeth 122. These teeth have a minimum or near minimum pitch and the cutter itself is mounted for rotation at abnormally high speeds in accordance with the process disclosed in the copending application mentioned. Thus the pitch of the cutting teeth will lie within the range of from $\frac{1}{64}$ of an inch to $\frac{1}{2}$ inch and the teeth are moved at a linear speed in excess of 1000 feet per minute to bring them into instantaneous contact with the metal work piece.

Figures 8 and 9 illustrate a segmental or built-up cutter intended for use in milling special sections, such, for instance, as that indicated by the letter Z in Figure 10. Referring to Figure 9, the cutter assembly comprises a cylindrical portion 130, a central grooved portion 132 and a second cylindrical portion 134 adapted to be held in assembled position by means of bolts extending through the members and also through annular clamping members 136, 138. As illustrated by means of dotted lines, the openings 149 extending through the cutter segments are of a diameter greater than the diameter of the bolts passing through them to allow for expansion during operation of the cutter.

In milling a bar of the shape indicated by the letter Z, the cylindrical portion 130 of the cutter and the flange 150 of the cutter 132 will mill the stem 152 of the bar and the grooved portion of the cutter 132 will mill the rounded head 154 of the bar. The cutter 134 will not be required for this particular operation. It will be understood that in an operation of this nature, the guide rolls which cooperate with the cutters will be correspondingly shaped to accommodate the side of the bar lying opposite to that engaged by the cutter. The number of stands or assemblies A, B, C, etc., and M, N, O, etc., that are employed for the purpose of milling the bar Z will be optional, it being observed however that at least one stand or assembly will be disposed in such a manner as to mill the flat face 156 of the bar.

In milling the bar X various types of operations can be carried out by the machine. The stands M, N, O, etc., might be employed to machine the side edges 158, 160 and the stands A, B, C, etc., to mill the top and bottom surfaces 162, 164, including the areas 166, 168. Here again the hard metal cutters and the cooperating guide rolls would be shaped to conform to the contour of the bar and such areas as 166 and 168 would be milled by cutting teeth formed on the face of the cutter, such as the face 170 as shown

in Figure 7 or 172 in Figure 9. The same method of treatment would apply to the bar Y and to any other special section as to standard sections such as angles, channels, H's, T's, strips, ovals, half ovals, half rounds, beams, channels, squares, flats, hexagons, etc.

A typical milling operation performed in accordance with the present invention may be described as follows: A cutter provided with carbide cutting teeth, driven at an R. P. M. of approximately 1500 and having a diameter of approximately 4 inches mills a flat bar to a depth of approximately $\frac{1}{2}$ of an inch. The bar flat during this operation is fed at a rate of 600 inches, or 50 feet, per minute and approximately 18 cubic inches of metal is thereby removed per minute. This operation can be performed with a four inch cutter, having a $\frac{1}{4}$ inch pitch and a $22\frac{1}{2}$ degree helix, on cast iron having a Brinell hardness of 200 or steel of the grade C 1020 having a Brinell hardness of 180. It is to be understood that the helical angle of the cutting teeth may vary, but ordinarily it will lie within the range of from 10 degrees to 30 degrees. The teeth themselves may have a 0 degree radial angle and the cutting extremities thereof may be provided with a desired negative angle such as 10 degrees.

Additionally, it is once more pointed out that the invention may be employed to operate on rough products such as billets, slabs, blooms, and the like, as will be readily apparent to those skilled in the art, without departing from the spirit of the invention as set forth in the appended claims.

Having thus described the invention, what we claim as new and desire to secure by Letters Patent of the United States is:

1. A machine for milling metal articles other than rounds, said machine comprising a plurality of stands, each of said stands including a cutter having a longitudinal axis, a cooperating guide roll mounted to engage a surface of said work opposite from said cutter and having a longitudinal axis, means for rotatably driving said cutter and roll about said axes, and means for simultaneously angularly adjusting the longitudinal axes of the cutter and roll and driving means therefor to predetermined positions throughout an arc of 180° .

2. A machine for milling metal articles other than rounds, said machine comprising a plurality of stands, each of said stands including a cutter having a longitudinal axis and having cutting teeth on the periphery thereof of a pitch not greater than one-half inch, a cooperating guide roll having a longitudinal axis, means for simultaneously angularly adjusting the longitudinal axes of the cutter and roll to predetermined positions throughout an arc of 180° , and means for rotating the cutter in said adjusted positions at a surface speed in excess of 1000 linear feet per minute.

3. A machine for milling metal articles other than rounds, said machine comprising a plurality of stands, each of said stands including a cutter having a longitudinal axis, a cooperating guide roll having a longitudinal axis, means for rotating the longitudinal axes of the cutter and roll through an arc of 180° , the said cutter being shaped to conform to the contour of the article being milled, means for rotating the cutter at a surface speed in excess of 1000 linear feet per minute, and means for rotating the guide roll at a surface speed in excess of the rate of feed

of the metal article to impart a burnishing action to said article.

4. A machine for milling metal articles other than rounds comprising a plurality of separate stands, a cooperating cutter and guide roll at each stand mounted for rotation about parallel axes, means at each stand for angularly adjusting said parallel axes to predetermined positions throughout substantially 180° to cause the cutters at the individual stands to engage selected surfaces of the article being milled, and means at each stand for rotatably driving the associated cutter about its axis in said positions.
